UNITED STATES PATENT OFFICE.

JAMES B. BROWN, OF DANBURY, CONNECTICUT, ASSIGNOR TO HIMSELF
AND WILLIAM H. HOWE, OF LYNN, MASSACHUSETTS.

HAT POUNCING AND SHAVING MACHINE.

SPECIFICATION forming part of Letters Patent No. 225,270, dated March 9, 1880.

Application filed February 2, 1880.

To all whom it may concern:

Be it known that I, JAMES B. BROWN, of Danbury, in the county of Fairfield and State of Connecticut, have invented certain new and useful Improvements in Hat Pouncing and Shaving Machines; and I do hereby declare the following to be a full, clear, and exact description of the same, sufficient to enable others skilled in the art to which the invention appertains to make and use the same, reference being had to the accompanying drawings, and the letters of reference thereon, which form part of this specification.

The invention relates to the organization in one machine of a pouncing and a shaving mechanism, in order to economize in machinery, time, and labor in finishing hats.

Heretofore separate machines have been employed for effecting the pouncing and shaving of hats, compelling the operator to handle the hats several times and consuming much time; but by my invention the two operations are performed in the time usually consumed in one by the old methods.

The invention consists in a machine provided with an ordinary pouncing-cone, in combination with an adjustable bed-lever having a shave or knife, substantially as hereinafter set forth.

In the accompanying drawings, in the several figures of which like parts are similarly designated, Figure 1 is a side elevation of my improved machine. Fig. 2 is a front-end view. Fig. 3 is a longitudinal vertical section of the pouncing-cone and its housings. Fig. 4 is a top view of the bed-shaving lever.

In suitable standards a a' are arranged housings b , to receive a shaft, c , which is driven by a pulley, d , connected with appropriate motive power. Of course the machine may be hand-driven without departing from this invention.

On the shaft c is an ordinary emery-faced or other suitable pouncing-cone, e .

f is a lever having a shouldered web, g , to fit in a slot or cavity, h , in the standard a , said lever being supported by a rod, i , connected to a foot-lever, k . One end, l , of lever f is arranged in line with and below the cone

e , and is concaved (see Figs. 2 and 4) to 50 match the curvature of the cone, and such end l forms the bed to receive the hat during the operating of pouncing and shaving. This bed is provided at one edge with a knife or shave, m , to operate against the inside of the 55 hat to shave it as the pouncing-cone e is operating upon the outside.

The rear end of lever f is confined against lateral displacement by a tongue, n , thereon loosely entering a recess, o , in the standard a' , such recess being sufficiently long to permit the requisite vertical play of the lever. At this end of the lever and upon it is arranged an eccentric disk, r , operating in connection with a gage-pin, s , to hold the bed l 65 up against the pouncing-cone during the operation of the machine the entire length of such bed, so as to insure even work on the surface of the hat.

It will be seen that I thus accomplish at 70 one operation of a single machine what has heretofore been done by two operations of separate machines, and the pouncing and shaving are thoroughly effected, thereby saving in machinery, time, and labor.

The bed l of the lever is made concave, in order to bring a greater surface of the hat under operation at a given time.

What I claim as new, and desire to secure by Letters Patent, is—

1. In a combined hat pouncing and shaving machine, a pouncing-cone and a knife or shave, substantially as and for the purpose described.

2. A machine for pouncing and shaving 85 hats, provided with a pouncing-cone and a shaving device for effecting the simultaneous pouncing and shaving of hats, substantially as specified.

3. In a hat pouncing and shaving machine, 90 a shaving-lever, in combination with an eccentric disk and gage-pin, substantially as specified.

4. A lever, f , provided with a hat-shave and an eccentric disk, in combination with an operating-lever and a detent for said disk, substantially as and for the purpose specified.

5. The combination of a pouncing-cone and

a lever having an opposed concave bed, substantially as specified.

6. An organized machine composed of mechanism for pouncing hats and devices for simultaneously shaving the same, substantially as specified.

In testimony that I claim the foregoing I

have hereunto set my hand this 19th day of January, 1880.

JAMES B. BROWN.
